BY ATTORNEY

UNITED STATES PATENT OFFICE.

JOHN Z. MAST, OF DENBIGH, VIRGINIA.

MAIL CRANE.

Application filed December 13, 1921. Serial No. 522,046.

To all whom it may concern:

Be it known that I, JOHN Z. MAST, a citizen of the United States, residing at Denbigh, in the county of Warwick and State of Virginia, have invented new and useful Improvements in Mail Cranes, of which the following is a specification.

This invention relates to a mail crane, the principal object of the invention being to provide means for easily and quickly placing the mail bag on the crane in a catching position and for so supporting it that it can be caught by the catching device on the car without interference upon the part of the holding means.

Another object of the invention is to provide means for raising and lowering the bag holding means so that the said means can be lowered to have the bag placed thereon and then raised into catching position.

This invention also consists in certain other features of construction and in the combination and arrangement of the several parts, to be hereinafter fully described, illustrated in the accompanying drawings and specifically pointed out in the appended claim.

In describing my invention in detail, reference will be had to the accompanying drawings wherein like characters denote like or corresponding parts throughout the several views, and in which;—

Figure 1 is an elevation of the invention. Figure 2 is a front view thereof.

Figure 3 is a longitudinal sectional view. Figure 4 is a cross sectional view.

In these views 1 indicates a hollow upright which is adapted to be placed along the track and the front of which is provided with a slot 2 which extends vertically, as shown, the side walls of the slot forming guideways for the sliding member 3. Sprockets 4 are mounted on shafts 5 in the upright and a chain 6 passes over said sprockets and is secured to the sliding member 3 so as to cause said member to move vertically when the chain is caused to travel over the sprockets. Shaft 7 is rotatably mounted in the upright and has one end projecting therefrom to receive a ratchet 8 and a crank handle 9. A dog 10 on the upright engages the ratchet to control the movement of the shaft. A sprocket 11 is mounted on this shaft and has its teeth engaging the rear part of the chain so that the chain will be moved when the shaft is

rotated by the crank. Thus the sliding member can be raised or lowered by rotating the crank in different directions and it will be held in adjusted position by the dog engaging the ratchet.

Brackets 12 are secured to the sliding member and blocks 13 are pivotally connected with said brackets by the vertically arranged pins 14 so that said blocks have turning movement in a horizontal direction upon the brackets. The upper bracket is provided with stops 15 for limiting the turning movement of the upper block. Mail bag supporting arms 16 are pivoted in said blocks by the horizontally extending pins 17 so that the arms can swing vertically and the upper arm is normally held in raised position by the spring 18 which is carried by the upper block. The two arms are connected together by the link 19 which connects the projecting end of the lower arm with the front arm at a point in front of the pivot so that when the upper arm is raised the lower arm is lowered and vice versa. The outer ends of the arms are notched to receive rings 20 on the mail bag A, the tendency of the spring to spread the arms apart acting to hold the bag in place. A bracket 21 is secured to the upright adjacent the bottom thereof and is arranged to engage the lower arm when the sliding member has been lowered to force said lower arm upwardly and thus facilitate the placing of the bags upon the arms as will be apparent.

From the above it will be apparent that the crank shaft is first turned, after releasing the dog, to lower the parts so as to bring the arms within reach to permit the placing of the mail bag thereon. This lowering of the parts will cause the lower arm to engage the bracket 21 so as to cause the arms to swing towards each other into bag receiving position. After the bag has been placed in position the crank shaft is turned in an opposite direction to raise the parts to place the bag in a position where it will be engaged by the catching device on the mail car. When this catching device strikes the bag the arms and blocks will swing horizontally in the direction the train is traveling, until brought to rest by the stops, thus removing strain off the parts and facilitating the removal of the bag from the arms.

I may also provide a pair of pulleys 22 for the chain 6 for keeping the same tight and preventing it from slipping and I may also

provide an electric lamp 23 on arm 16 which is supplied with current from the battery 24, a suitable switch being located in the circuit for controlling the same. This lamp 5 is desirable when the mail bag is placed on the device at night.

It is thought from the foregoing description that the advantages and novel features of my invention will be readily apparent.

10 I desire it to be understood that I may make changes in the construction and in the combination and arrangement of the several parts, provided that such changes fall within the scope of the appended claim.

15 What I claim is:—

A mail crane comprising a hollow upright, a vertically movable member thereon, sprockets within the upright, a chain passing over the sprockets and connected

with the member, a crank shaft carried by 20 the upright, a sprocket thereon engaging the chain, ratchet means associated with the crank shaft for holding the vertically movable member in adjusted position, brackets on the upright, a block pivoted to move about a vertical axis on each bracket, an arm pivoted to each block to move about a horizontal axis, a link connecting the arms together, spring means tending to move the upper arm upwardly and a bracket at the 30 lower part of the upright for engaging the lower arm for moving the arms towards each other.

In testimony whereof I affix my signature.

JOHN Z. MAST.
